INJECTION SYRINGE

Josef Schoene, Berlin, Germany

Application December 23, 1933, Serial No. 703,767
In Germany December 24, 1932

5 Claims. (Cl. 128—218)

My invention relates to improvements in medical injection syringes, and refers more particularly to all-glass syringes. Such syringes, while having numerous advantages over all-metal syringes, also have the disadvantage that the glass piston of the syringes is apt to damage the bottom of the syringe cylinder by striking it too hard. Moreover syringes of the all-glass type share with all other injection syringes the inherent defect, that even after the syringe has been thoroughly sterilized by boiling, certain lasting form of bacteria nullify the effect of this sterilization by developing during the periods in which the syringe is not in use.

15 The present invention is intended to obviate these deleterious defects and aims to produce a better syringe of this type.

First and foremost, the dome or cone at the working extremity of the piston of the type of 20 syringe made according to the present invention, is provided with a layer of absolutely pure silver, which in the first instance mitigates the shock occurring when the piston reaches the bottom of the cylinder, while at the same time it 25 frees the interior of the syringe of all bacteria or germs, and keeps the interior sterile by reason of the oligodynamic action of the silver.

Although for oligodynamic purposes, the silver 30 layer might be situated at any part of the interior of the syringe, there are special advantages to be obtained by applying the silver to the dome or cone of the working face of the piston. As the silver is thus centrally situated, the oligodynamic action, because the piston is 35 movable within the cylinder, is to a certain extent also made movable, and is able to act at a great many points. The fixation of the silver layer on the dome of the piston may be effected in any suitable manner.

40 The dome of the piston may be made electrically conductive by means of a silver solution fused into the same in a known manner and the pure silver being electrolytically deposited thereon.

45 The appended drawing illustrates two embodiments of the syringe and its accessories or component parts.

Fig. 1 is a vertical longitudinal section through 50 one of the embodiments.

Fig. 2 is a similar illustration of a somewhat modified syringe.

Figure 3 represents an illustration of a component part, viz. a shock absorbing device for the piston.

Figure 4 is a detail in perspective of the shock absorbing device of Fig. 3.

In Figures 1 and 2 a so called all-glass syringe is represented, where *a* indicates the glass syringe cylinder body, *b* the glass syringe piston, *c* the metallic threaded needle carrier fused into the glass syringe bottom, *d* denotes the hollow injection needle, and *e* in Figure 3 a preferably hexagonal finger support provided on the syringe cylinder. According to the present invention, 10 a comparatively thick layer *h* (or *h'* in Fig. 3) of silver is fixed or applied to the dome of the piston of the syringe in any known manner as by electricity. This layer of silver mitigates the effect of the piston striking the bottom of 15 the syringe body, at the same time keeping or making the interior of the syringe sterile and germ free by means of its oligodynamic action. In Fig. 1 the layer *h* is secured to the piston by means of a screw *i* but this may be eliminated as seen in Fig. 2.

As is well known, the oligodynamic action of the pure silver is an action of the silveroxide produced by the action of the oxygen in the air or by other action and increased or reduced 25 by means of an H_2O_2 solution or by means of manganese dioxide or other oxidization carriers.

An especially strong, long lasting, resisting and visible oligodynamic action is attained, for example, if a somewhat concentrated, neutral, acid 30 or alkaline solution of potassium hyper manganese is allowed to act on the silver dome of the piston of the syringe. This causes the formation of a chemical double compound of silver oxide and manganese dioxide ($Ag_2O—2MnO_2$). 35 The silver oxide-manganese dioxide formed by alkaline potassium permanganate solution has been found to be especially suitable and advantageous. It possesses great resistance in respect to boiling and the action of dry heat as well as 40 against the action of sulphur ions (sulphuretted hydrogen) and reducing substances, such as novocaine, or the like, which reduce or nullify the oligodynamic action of the pure silver, which has been activated and increased by the manganese dioxide.

The manganzation of the silvered dome of the syringe piston *b* by means of $Ag_2O—2MnO_2$ is effected in the most simple manner by immersing the dome of the piston for 1 to 2 hours in, for 50 instance, a glass tube filled with a solution of potassium permanganate to a height of approximately 1 cm.

The protection offered to the syringe by reason of the shock absorbing effect of the pure silver 55

dome of the piston may be further increased by means of a shock absorbing and braking device *g* for the piston *b* which is shown assembled in Figs. 2 and 3. This device *g* in the nature of a 5 clip prevents on the one hand the accidental sliding or slipping of the syringe piston by exerting a lateral pressure on the periphery of the same and also eliminates the sharp impact of the piston on the bottom of the syringe, by engaging the abutment *f* of the same at the very moment of impact or a little beforehand. The abutment *f* on the 10 syringe piston stem strikes upon the shock absorbing piston brake *g* and thereby slows down the movement of the piston.

15 I claim:

1. An injection syringe having a glass cylinder and a glass piston, and a buffer-like pad of soft metal formed on the working end only of said piston as an extension thereof.
2. An injection syringe having a glass cylinder 20

and a glass piston, a buffer-like pad of soft metal formed on the working end of said piston as an extension thereof and contacting the cylinder wall, and said metal having sterilizing properties.

3. An injection syringe having a glass cylinder 5 and a glass piston, and a buffer-like pad of pure silver formed on the working end of said piston as an extension thereof and engaging the cylinder wall.

4. An injection syringe having a glass cylinder 10 and a glass piston, a layer of pure silver on the working face of said piston, and a coating for said silver to augment the sterilizing action of the same.

5. An injection syringe having a glass cylinder 15 and a glass piston, a coating of pure silver on the working face of said piston, and a coating of the double compound silver oxide manganese dioxide ($Ag_2O-2MnO_2$) on said silver.

JOSEF SCHOENE. 20
